UNITED STATES PATENT OFFICE.

GARRET A. GARRISON, OF PATERSON, NEW JERSEY.

WARDROBE.

SPECIFICATION forming part of Letters Patent No. 315,760, dated April 14, 1885.

Application filed August 18, 1884. (No model.)

To all whom it may concern:

Be it known that I, GARRET A. GARRISON, a citizen of the United States, residing at Paterson, Passaic county, State of New Jersey, have invented a new and useful Improvement 5 in Wardrobes, of which the following is a specification, reference being had to the accompanying drawings, forming a part thereof.

The object of my invention is to provide a 10 wardrobe of such construction as to be handled, folded, and used with facility, which objects I attain by the construction which will be hereinafter fully explained, and pointed out in the claim.

15 Figure 1 of the drawings shows my invention in perspective with a portion of the front open. Fig. 2 is a plan view in perspective showing the method of folding, &c.; and Fig. 3 is a vertical section showing shelves, hinges, 20 cords, &c.

A represents a portable folding wardrobe constructed, mainly, of textile fabric or cloth *a*, which cloth or textile material is secured, suitably, to the inside of a frame composed of wood 25 having a front part, *b*, and ends *h*, which parts are suitably mitered at the corners *b'*, where they meet, and are secured together adjustably by means of suitable hinges, *f*. The ends of the frame are secured at the back to brackets 30 *g*, which brackets are provided with suitable eyes, *g'*. To the inside of the frame there is arranged cords *k'*, having a loop on their lower end to accommodate a hook, *k*, arranged for the same in shelves *c c'*, which shelves are hinged 35 together, as shown at *c*², Fig. 3. The shelves *c c'* are provided with hooks at each end of the same, upon which may be hung various articles of clothing, &c. The back portion of the cloth is taken up and across the top, and is secured 40 on cleats arranged therefor on the inside of the ends *h* and front *b*, the end cleats supporting the top in the manner shown in Fig. 1. The textile material is joined at the corners in the usual way, and is suitably secured to 45 the bottom, which is composed of parts *d d'* that are hinged together, as shown at *d*², Fig. 3.

In practice the wardrobe is hung to the fastenings prepared therefor against the wall

or elsewhere, the eyes *g'* passing over such fastenings, which suspends the wardrobe to 50 its fastenings, after which the hinges *f* are opened in position, as shown in Fig. 1, after which action the shelves *c c'* adjust themselves by gravity to their suspended positions on the cords *k'*, the lower ends of which are looped 55 over the hooks *k*, after which the various articles of clothing, &c., may be laid on the shelf *c c'* and bottom *d d'* by opening the front edges, *e*, as shown in Fig. 1. The cords *k'* may be lengthened or shortened on the pins *k*³ to 60 raise or lower the shelf *c c'* to any position desired. The hooks *n* may be used for hanging up dresses, &c. My invention may be folded and packed in a trunk by closing the 65 hinges *f* and removing the brackets *g* from their fastenings at *g'*, after which the ends *h* are thrown inward, as shown in Fig. 2, and the frame rolled up in the cloth *a*. When the shelf *c c'* is reached, the parts are doubled up by means of the hinges *c*², and the folding continued until the entire structure is rolled up, 70 after which the same can be laid in a trunk or packed away in a small compass elsewhere, and is particularly well adapted for persons who travel, as it furnishes them with a light, 75 cheap, and convenient means of accommodation for their clothes and other necessary articles, and can be hung up in many places for convenience where the ordinary wardrobe could not be used. 80

Having described my invention and its use, what I claim, and desire to secure by Letters Patent, is—

The combination of the cloth *a*, the frame *b h*, for securing said cloth, the hinges *f*, for holding the frame *b* and *h* in position, brackets *g*, having eyes *g'*, for suspending the top and cloth, bottom *d d'*, for securing the bottom of the cloth, shelf *c c'*, suspended from the top or frame *b* and *h* by cords *k'*, and hooks or pins 90 *k*³, *k*, and *n*, substantially as described.

GARRET A. GARRISON.
